UNITED STATES PATENT OFFICE.

WILLIAM NELSON, OF WHITEPLAINS, NEW YORK.

SHADE AND CURTAIN HANGER.

SPECIFICATION forming part of Letters Patent No. 793,899, dated July 4, 1905.

Application filed October 10, 1904. Serial No. 227,885.

To all whom it may concern:

Be it known that I, WILLIAM NELSON, a citizen of the United States, residing at Whiteplains, in the county of Westchester and State of New York, have invented a new and useful Shade and Curtain Hanger, of which the following is a specification.

This invention is a combination shade-roller and curtain-bracket, the object being to provide an exceedingly cheap, simple, and efficient combination device which can be quickly and easily attached to and detached from the window-frame.

Another object of the invention is to provide a device which can be made to fit various widths of window-frames or corner-blocks; and another object is to provide the device in which the bracket proper can have a limited amount of vertical adjustment, so as to insure a level position for the shade-roller and curtain-pole.

The invention consists in the various features of construction and combination, all of which will be fully described hereinafter and pointed out in the claims.

In the drawings forming a part of this specification, Figure 1 is a perspective view showing the practical application of my invention, the curtain-pole being omitted for the purpose of more clearly illustrating the invention. Fig. 2 is a side elevation, partly in section. Fig. 3 is a detail perspective view of one of the devices attached to the window-frame. Fig. 4 is a top plan view. Fig. 5 is a detail perspective view of the roller-bracket proper, and Fig. 6 shows a detail of a slight modification.

In carrying out my invention I employ the shade-brackets proper, A, comprising bearing portions A', and a plate A², integral with the bearing portion and provided with horizontal threaded ears A³. Clamping-rods B and C have their threaded ends B' and C' screwed into the threaded ears A³, the rod B passing through a casting D, provided with a rearwardly-extending barbed finger D', which is adapted to engage the upper face of the window-frame, the rod B having a square head B² resting upon the casting D, and by

turning the said rod with a wrench the casting can be tightly clamped against the upper side of the window-frame, and the lower end of the rod C is bent inwardly and provided with barbs, as shown at C², so that when the casting D is clamped against the top of the frame the ends C² will be brought into engagement with the lower face of the same. It is obvious, therefore, that the shade-roller brackets can be securely fastened to the window-frame without the use of nails or screws. I also provide a curtain-pole bracket E, which is formed of wire and comprises the rest portion E' and the bracket-arms E² and E³, the end of the arm E² being threaded, as shown at E⁴, and adapted to screw into the aperture A⁴ produced in the plate A², and the end E⁵ of the arms E³ is adapted to fit into the socket A⁵ produced in the plate A² adjacent its lower end. A pole-bracket constructed as herein shown and described can be quickly and easily attached to and detached from the shade-roller bracket whenever desired.

In Fig. 6 I have shown a bail F, which extends across the lower ear A³ and is provided with barbed ends F' for the purpose of engaging the sides of the window-frame or corner-block whenever it is desired to make the attachment particularly secure.

It will thus be seen that I provide an exceedingly cheap, simple, and efficient combination shade-roller and curtain-bracket, which can be quickly and easily attached to the window-frame without the use of nails or screws.

Having thus fully described my invention, what I claim as new, and desire to secure by Letters Patent, is—

1. The combination with the shade-roller bracket, provided with threaded ears, of the threaded rods one of which is formed with a hooked and barbed end, and a clamping casting through which the opposite end of the other rod is adapted to pass, as set forth.

2. The combination with the shade-roller brackets, having threaded ears, of the threaded rods adapted to engage said ears and a curtain-pole bracket detachably connected to the shade-roller bracket, as set forth.

3. The combination with the shade-roller bracket, comprising a plate having a threaded aperture near the upper end, and a socket near the lower end, of a pole-bracket comprising the rest portion and the bracket-arms, one of said bracket-arms having a threaded end adapted to engage the threaded aper-

ture, the end of the other arm being adapted to fit into the socket as set forth.

WILLIAM NELSON
